UNITED STATES PATENT OFFICE.

CYPRIEN O. MAILLOUX AND HENRY J. WESTOVER, OF NEW YORK, N. Y.

GAS-ANALYZER FOR FURNACES.

942,861.

Specification of Letters Patent.

Patented Dec. 7, 1909.

Original application filed February 7, 1907, Serial No. 356,188. Divided and this application filed April 22, 1907. Serial No. 369,469.

To all whom it may concern:

Be it known that we, CYPRIEN O. MAILLOUX and HENRY J. WESTOVER, citizens of the United States, residing in the city, 5 county, and State of New York, have invented a certain new and useful Improvement in Gas-Analyzers for Furnaces, of which the following is a specification.

Our present invention relates to certain 10 improvements for use in connection with apparatus for indicating the proportion of carbon dioxid in furnace gases and is equally applicable in connection with apparatus for automatically regulating the supply of air 15 for furnaces in accordance with variations in the proportion of carbon dioxid in the gases produced therein.

This is a division of our prior application 20 for Letters Patent, Serial Number 356,188, filed February 7th, 1907, wherein the apparatus herein shown is specifically claimed in combination with certain devices for automatic regulation of air for furnaces.

One principal object of our present invention 25 is the provision of means whereby a single carbon dioxid analyzer may be brought into operative relations with a number of furnaces and corresponding indicators.

Another object of this invention is the 30 provision of means whereby a carbon dioxid analyzer which draws the gas to be analyzed from a distant furnace may be supplied at all times with furnace gas freshly brought from the furnace and therefore representative at all times of actual furnace conditions.

Our invention is illustrated in a certain preferred embodiment in the accompanying drawings wherein—

Figure 1 is an elevation of the entire device, Fig. 2 is a vertical section of a combined gas director and commutator, Fig. 3 is a top view of the operative circuit closer at the master instrument and of one of the relays which may be used therewith, Fig. 4 is a development of the surface of the commutator, showing in diagram one way in which a number of relays may be operated in rotation and Fig. 5 shows one form of pipe clearing means in section.

It is to be understood that our present invention is independent of the particular form or construction of automatic apparatus for analysis of gas whereby the operative circuit is closed, as many forms of such devices are already well known, any one of

which might be adapted to use with this improvement without departing from our invention. The form of analyzer shown in Fig. 1 of the accompanying drawings is merely illustrative and is not to be understood as at all essential.

The particular analyzer shown in Fig. 1 is that known on the market as the "Sarco" analyzer and will require only very brief description here. Within the cylindrical chamber 1 there is a float which falls when connected to the draft in the furnace chimney by the automatic valve 2, and rises again when the same valve connects it with atmosphere. The cord 3 is attached to said float and, passing over the pulley 4, carries at its end the reservoir 5. A weighted tilting lever 6, pivoted at 7, is pushed back and forth alternately by the pins 8 and 9, and its shorter arm acting on the fork 10 is thus made to operate the slide valve 2, in such a manner as to cause the float within the chamber 1 to move up and down, causing reciprocating rotary movement of the wheel 4 and vertical movement of the reservoir 5. The reservoir 5, containing displacing liquid and being connected to the pumping chamber 11, by the flexible tube 12, admits a sample of furnace gas through the inlet pipe 13 and then forces this measured sample over 80 through the tube 14 to the absorption chamber 15, containing a solution of lye. The displacement of absorbing liquid thus caused depends upon the amount of residual gas after absorption of carbon dioxid, and this 85 displacement is measured for each operation of the analyzer by the extent to which the float 16 is lifted in the chamber 17. The movements of this float are transmitted by the balanced lever 18 and pivoted rod 19 to 90 the stylus 20, whereby a vertical line is drawn upon the cylindrical chart surface 21 which is slowly rotated by any appropriate means. In Figs. 1, 3 and 4 is shown one 95 form of device whereby exterior electric circuits may be selectively controlled by this form of analyzer. A variety of devices are well known in this art for utilizing such circuits for indicating purposes and description 100 of such devices will be unnecessary here. The pivoted rod 19 is embraced loosely by the rear extension 22 of a circuit closing bridge 23 of magnetic material supported 105 normally on the stylus 20. As the stylus moves up and down, this bridge moves like-

wise opposite a pair of conducting rails 24, 25, one of which is interrupted at 26 as shown in Fig. 4. Behind the rails 24, 25, we place an electro-magnet 27 with an extended pole piece 28, so placed that, when this magnet is energized, the bridge 23 is attracted against the rails 24, 25. As heretofore explained, the maximum height to which the stylus and bridge are carried by movement of the float 16 depends upon the volume of residual gases in the absorption chamber 15 and therefore on the proportion of carbon dioxide which is in each sample of furnace gas. The point of interruption 26 is therefore so placed that it will be opposite that position of the bridge 23 which corresponds to the ideal proportion of carbon dioxide. If the carbon dioxide is in excess the maximum height of the bridge 23 will occur below 26 and, if the magnet 27 is then energized, the bridge will be drawn into contact with the lower section of the rail 25, connecting it electrically with the rail 24. If the carbon dioxide is deficient connection will be caused between 24 and the upper section of 25. We therefore provide means for energizing the magnet 27 at the moment when the bridge 23 is at its maximum height and for this purpose we prefer the devices shown in Fig. 1. Here one terminal of 27 is connected to one pole of the battery 29, whose opposite pole is connected to the spring terminal 30 on the lever 6. The second terminal of 27 is connected to the pin 9. Thus, at the moment that pin 9 operates valve 2 so as to lower the reservoir 5 (which occurs at the end of each operation and with the float 16 fully raised) the circuit of 27 is closed at 30.

40 One simple form of indicator operable by the means thus far described is shown as an illustrative example in Fig. 3. Here a polarized relay 31, provided with oppositely wound coils 32, 33, connected respectively to the two sections of the interrupted rail 25 acts on the pointer-armature 34, whose position at the end of each analysis therefore indicates whether the carbon dioxide is in excess or not. If the pointer 34 hangs vertically after any given analysis it indicates the existence of the proper desired proportion of carbon dioxide in the furnace.

One branch of our present invention relates to means whereby, just after each operation of the analyzer, the entire apparatus may be brought into relation with a new furnace and its corresponding indicator. For this purpose a separate gas conveying pipe 35 brings gas from each furnace to a 55 gas-directing apparatus comprising a stationary support 36 and a rotary valve 37 containing a gas-directing passage 38. One end of the passage 38 registers successively with the different pipes 35 as the valve body 37 is rotated, while the opposite end of the

passage 38 registers permanently with the inlet pipe 13. Rotation of 37 is preferably accomplished by the magnet 39, connected in series with 27 and acting through the lever 40, ratchet 41 and ratchet-wheel 42. At the same time that the pipes 35 are thus successively connected to the analyzer, corresponding indicator coils are also successively brought singly into circuit with the rails 24, 25. For this purpose the cylindrical surface of the body 37 is provided with a conducting strip 43 having a projecting tongue 44. A single brush 45, connected to one pole of a generator 46 makes continuous contact with the strip 43, while separate brushes 47, are placed symmetrically around the body 37 so as to make contact successively with the tongue 44. Each brush 47 is permanently connected to both indicator coils 32, 33, as shown in Fig. 4, and the opposite ends of these coils are respectively connected to the through wires 48, 49, connected respectively to the two sections of the rail 25. From this it will be seen that, as the magnet 39 is energized after each operation of the analyzer, a new furnace tube 35 and a new indicator will be automatically placed in operative relation to the master instrument after each analysis.

Another branch of our improvement has relation to means whereby the sample of gas drawn in for each analysis shall represent always the latest condition of the furnace to be tested. Where the master instrument is located at some distance from the furnaces, the pipes conveying gas samples are necessarily long, and unless means were supplied to correct the error, each analysis would show only the conditions existing in that part of the conveying tube near the instrument which might often differ materially from those actually existing in the furnace. To obviate this difficulty, we prefer the means shown in Figs. 1 and 5 wherein a rotary valve 48 is operated momentarily after each analysis by means of the solenoid 50 in series with 39 and 27, which solenoid acts by core 51 and lever 52 to rotate the valve in one direction. The spring 53 acts to return said valve. Steam is led by the pipe 54 to the valve 48 and, when the solenoid 50 is energized (see Fig. 5) this steam passes by pipe 55 to the inspirator 56, discharging at 57. In this position of the rotary valve 48, the passage 58, which is in permanent communication with the inlet pipe 13 on the side toward the furnace, admits gas through said pipe to the inspirator and the steam issuing at 57 draws with it the gas in the pipe 13 and whichever of the pipes 35 is at the time in communication with it. The entire line of pipe to the furnace is thus cleared out and, at the conclusion of the operation, the gas which is left near the analyzer is a specimen properly

representative of the condition of the furnace at the time. As soon as the solenoid 50 ceases to be energized, the spring 53 turns the valve 48 through 90°, interrupting communication between the steam pipe 54 and the inspirator, and bringing the passage 58 into communication with the opening 59 (see dotted circle in Fig. 5) which opening leads directly to the inlet pipe 13 next to the analyzer. The valve is thus in condition to permit the next operation of the analyzer to draw in a specimen of gas from one of the conveying pipes 35.

It should be explained here that the gas directing means and conveying pipes are diagrammatically shown in Fig. 1 for the sake of convenience, and that the correct relation of sizes is shown in Fig. 2.

A variety of changes can be made in this apparatus without departing from our invention and we are not to be limited to the details herein shown and described.

What we claim is:

1. In combination, an automatic gas analysis apparatus, a plurality of pipes for delivering the gaseous products of combustion from a plurality of furnaces, a directing valve by which each of said pipes, one after another communicates with said gas analysis apparatus, and means for operating said valve controlled by the movement of the said gas analysis apparatus, substantially as described.

2. An automatic CO₂ analyzer, a plurality of gas conveying pipes, a directing valve with which said pipes communicate for placing them one after the other in operative relation with said analyzer, electro-magnetic means for moving said valve and a circuit controlled by movement of said analyzer for energizing said valve-moving means, substantially as described.

3. In combination, an automatic gas analyzing apparatus, a gas-directing means having entrance pipes arranged around a common center, a revoluble directing pipe placed so as to register at one end with said entrance pipes successively, and electro-magnetic means controlled by said analyzer for turning said directing pipe step-by-step, substantially as described.

4. A device of the class described comprising an analyzer, a gas-conveying pipe therefor, clearing means for said pipe, an actuating

device for said clearing means and automatic means controlled by said analyzer for causing operation of said actuating device, substantially as described.

5. A device of the class described comprising an analyzer, a gas-conveying pipe therefor, a gas-directing device inserted in the course of said pipe, clearing means for said pipe, an actuating device for said clearing means and automatic means controlled by said analyzer for causing substantially simultaneous operation of said gas-directing device and of said actuating device, substantially as described.

6. A device of the class described comprising an analyzer, a gas-conveying pipe therefor, a clearing means for said pipe, an electro-magnetic actuating device for said means and a circuit closer operated by said analyzer for energizing said actuating device, substantially as described.

7. A device of the class described comprising an analyzer, a gas-conveying pipe therefor, a clearing means for said pipe, an electro-magnetic actuating device for said means, an exit for the analyzer, an electric circuit for said actuating device and means for both operating said exit valve and closing said circuit, substantially as described.

8. In combination, a gas analysis apparatus, a plurality of pipes for delivering the gaseous products of combustion from a plurality of furnaces, a device for bringing each of said pipes, one after another into communication with said gas analysis apparatus, and operating means for said device automatically actuated by said gas analysis apparatus, substantially as described.

9. In combination, a gas analysis apparatus, a number of pipes for bringing gases from different furnaces, an equal number of indicators, a device for bringing said pipes and said indicators one after the other into operative relations with said gas analysis apparatus whereby the composition of the gas from each furnace is indicated on its corresponding indicator, said device being automatically actuated by said gas analysis apparatus, substantially as described.
